CLAIM

The ornamental design for a bracelet with shark figure, as shown and described.

DESCRIPTION

FIG. 1 is a front perspective view of a bracelet with shark figure showing our new design.

FIG. 2 is a front view of the bracelet with shark figure of FIG. 1.

FIG. 3 is a right side view of the bracelet with shark figure of FIG. 1.

FIG. 4 is a rear view of the bracelet with shark figure of FIG. 1.

FIG. 5 is a left side view of the bracelet with shark figure of FIG. 1.

FIG. 6 is a top view of the bracelet with shark figure of FIG. 1; and,

FIG. 7 is a bottom view of the bracelet with shark figure of FIG. 1.

The broken lines represent portions of the bracelet with shark figure that form no part of the claimed design.

1 Claim, 7 Drawing Sheets
